(57) **CLAIM**

We claim the ornamental design for a bicycle carrier rack, as shown and described.

DESCRIPTION

FIG. 1 is a perspective view of a bicycle carrier rack;

FIG. 2 is a front elevational view thereof;

FIG. 3 is a rear elevational view thereof;

FIG. 4 is a top plan view thereof;

FIG. 5 is a bottom plan view thereof;

FIG. 6 is left side elevational view thereof; and,

FIG. 7 is a right side elevational view thereof.

The mounting straps are shown in alternate positions in the figures.

The broken lines are directed to environment and are for illustrative purposes only; the broken lines form no part of the claimed design.
